TOY PROJECTILE-SHOOTING GUN

Anthony N. Smith and Donald V. Godfrey, Girard, Pa., assignors to Louis Marx & Company, Inc., New York, N. Y., a corporation of New York

Application November 8, 1941, Serial No. 418,350

6 Claims. (Cl. 124—27)

This invention relates to toys, and more particularly to toy guns which shoot a simulated projectile.

The primary object of the invention is to generally improve toy guns. A more particular object is to provide a toy simulating a portable trigger-operated gun such as a pistol or rifle. A further object is to design the same for use with a simplified magazine for holding and gravitationally feeding a supply of projectiles to the gun, said magazine preferably being detachable for more compact packaging of the toy.

Another object is to provide a simplified and dependable trigger and ejector finger mechanism, including a single spring acting as a main ejector spring. A still further object is to provide projectile stop means to prevent the projectile from sliding gravitationally out of the gun when the gun is pointed downwardly, as is often done with a portable gun.

To the accomplishment of the foregoing and other more specific objects which will hereinafter appear, our invention consists in the toy gun elements and their relation one to the other, as hereinafter are more particularly described in the specification and sought to be defined in the claims. The specification is accompanied by drawings in which:

Fig. 1 is an end elevation of a toy revolver embodying features of our invention;

Fig. 2 is a front elevation of the same;

Fig. 3 shows a projectile used with the gun;

Fig. 4 illustrates the internal appearance of the gun with one of the sides removed;

Figs. 5, 6 and 7 are perspective views showing successive stages in the operation of the trigger mechanism;

Fig. 8 is a transverse section drawn to enlarged scale, and taken approximately in the plane of the line 8—8 of Fig. 4;

Fig. 9 is a horizontal section illustrating the detent for the ejector finger;

Fig. 10 is a perspective view of the breech portion of the guide tube for the projectiles;

Fig. 11 is a bottom view of the same;

Fig. 12 is explanatory of a modification embodying a retractable stop for preventing the projectile from sliding gravitationally out of the gun;

Fig. 13 illustrates a modification employing a resilient projectile stop means for the same purpose;

Fig. 14 shows the application of the invention to a toy rifle; and

Fig. 15 is a fragmentary section drawn to en-

larged scale and taken approximately in the plane of the line 15—15 in Fig. 14.

Referring to the drawings, and more particularly to Figs. 1 and 2, the toy there shown simulates a revolver and comprises a gun body 12, including a barrel portion 14, a simulated magazine 16, a pistol grip 18, and a trigger 20. The true working magazine is disposed over the breech portion of the gun, as is indicated at 22, and carries a series of vertically superposed projectiles 24.

The mechanism of the gun is shown in Fig. 4, and comprises an ejector finger 26, the upper end of which is movable through a slotted projectile guide tube 28. The lower end of finger 26 is pivoted at 30 to the aforesaid trigger 20, the latter being pivoted at 32 on a frame 34. A main-spring 36 has its forward end connected to frame 34 at lug 38, while its rear end is connected to ejector finger 26 at 40. The ejector finger is preferably notched at 40 to hold the spring in place.

The upper end of finger 26 is normally held in rearward position by a detent 42, acted on by a thin wire spring 44. A heavy wire link 46 extends forwardly from detent 42 to a point in the path of the upper end of the trigger (the part just below the bent end 48). The construction of the detent 42 and link 46 is better shown in Fig. 9, in which the holding position of the detent is shown in solid lines at 42, while the released position is shown in broken lines at 42'. The detent is pivoted at 50 on a flange 52 turned downwardly from one side 54 of the frame 34, and is provided with a sidewardly projecting arm 56 to which is connected the upwardly turned rear end 58 of link 46. The forward end of link 46 is bent transversely at 60 and then reversely at 62, the latter part riding between the side walls of the frame. One side wall is preferably bent or channeled outwardly at 64 to additionally hold and guide the link 46.

The operation of this mechanism may be explained with reference to Figs. 5 through 9 of the drawings. In Fig. 5 the parts are shown in their position of rest. The lower end of ejector finger 26 has been pulled forward by the action of spring 36, and the finger 26 has moved the trigger 20 to forward position. As the trigger is drawn rearwardly to fire the gun, the parts assume the relation shown in Fig. 6, in which it will be seen that the lower end of the ejector finger 26 has been pulled rearwardly against the tension of spring 36 (now greatly stretched), while the upper end of finger 26 is held against forward movement by detent 42. The upper end 48 of the trig-

ger moves forwardly and approaches the cross bar 60 of link 46.

As the full stroke of the trigger is completed, the upper end of the trigger bears against the cross bar 60 of link 46, and pulls the link forwardly (see broken line position in Fig. 9), thereby moving the detent 42 out of the path of the ejector finger, which then moves abruptly and forcibly forward from the broken line position 26' in Fig. 7 to the solid line position 26 in that figure. The movement of the ejector finger is finally arrested by the sidewardly bent lug 48 at the upper end of the trigger. When the trigger is released by the operator of the gun, the parts are restored to the rest position shown in Fig. 5 by the action of spring 36.

The magazine 22 (Figs. 1 and 2) is preferably formed by bending a piece of relatively heavy stiff wire to inverted U-shape. The upper end 70 (Fig. 1) is curved on a radius large enough to receive the cylindrical projectiles 24. The substantially parallel legs 72 therebeneath are disposed somewhat closer together and are dimensioned to fit in a circumferential groove 74 (see Fig. 3) formed on each projectile. The projectiles are preferably turned out of wood, and are light enough to be harmless in flight. The lower ends of the legs 72 are bent outwardly as is indicated at 76 in Fig. 8 so as to clear the lowermost projectile, in order not to interfere with its ejection when the gun is fired.

The magazine is preferably detachable from the gun body for more compact packaging of the gun during shipment and sale. For this purpose, the lower ends of the legs of the magazine are received in ears 78 (see Figs. 10 and 11) which are bent outwardly from the guide tube 28. The latter is cut away on top to permit the downward feed of projectiles, and the ears 78 may be formed from some of the cut-away metal. The top of the gun housing is also cut away to clear the projectiles, as is indicated at 80 in Fig. 8, and the edges of the resulting slot are preferably notched or recessed at 82 to receive the guide wires 72 of the magazine. In this way the magazine is held upright, but may be removed by pulling the same upwardly while squeezing the side legs 72 together somewhat (the magazine being empty during its removal).

The guide tube 28 is preferably made of a single piece of relatively light gauge sheet metal, which is bent downwardly and substantially closed at a bottom seam 84 best shown in Fig. 11. A relatively long slot 86 is cut through the bottom of the guide tube near its breech end in order to accommodate movement of the upper end of the ejector finger 26. The edges 88 (Fig. 11) leading into slot 86 may, if desired, be made divergent to insure proper guidance of the ejector finger into the slot. A part of the guide tube is turned downwardly at 90 (Fig. 10) to act as a stop which prevents rearward movement of the lowermost projectile. Lugs or tongues 92 (Figs. 10 and 11) are bent outwardly at the rear end of the guide tube, and pass through mating slots 94 (Fig. 2) in the housing of the toy gun, this fixing the position of the tube.

The gun housing is made of oppositely dished halves pressed from heavy gauge sheet metal and secured together in edge to edge relation by appropriate connections, such as the tongue and slot connections 96 (Fig. 2) and the eyelet 98. The barrel is double walled, the smaller diameter guide tube 28 being housed within the larger-diameter externally-visible barrel 14. This gives

the toy rigidity and strength, and brings the projectile diameter down to a better and more realistic proportion to the outside diameter of the gun barrel. The forward end of the guide tube is properly centered in concentric relation with the outside barrel 14 by means of relatively tiny, inconspicuous dots 100, struck inwardly near the muzzle end of the gun. In the present case there are four such dots, two on each side, and they are so dimensioned as to just reach and bear against the outside of the guide tube, thereby centering it relative to the gun barrel.

The frame 34 within the gun is made of two pieces of sheet metal, the ends of which are appropriately flanged to space the same apart. These walls are secured together in conventional fashion by tongue and slot connections. The frame is also provided with outwardly directed tongues which pass through mating slots in one side of the pistol housing, these being indicated at 102 in Fig. 2.

If desired, the simulated revolving magazine 16 may be given a finish contrasting with the remainder of the gun body. In a typical case, the latter may be made of black and the former may be given a lustrous nickel or copper color which is attractive to children. This may be done most conveniently by adding separate covering sheets of metal at the magazine. This is most clearly shown in Fig. 8, in which the separate outer pieces are marked 106, and are secured to the gun body at the top and bottom by suitable bent tongue and slot connections. By making these parts of separate pieces of metal, they may be plated as a separate process, in no way affecting the overall black coating of the main parts of the gun body. The pieces 104 and 106 may be made of very thin metal, as they are supported by the heavier gauge walls inside.

Inasmuch as a portable gun such as a pistol or rifle may frequently be pointed downwardly, it is preferred to provide means to prevent the projectiles from sliding out of the guide tube. One arrangement for this purpose is illustrated in Fig. 12, in which the gun is additionally provided with a projectile stop 108, appropriately secured, as by spot welding at 110, to the bottom of the guide tube. The free end of resilient wire 108 is bent downwardly and then rearwardly at 112, where it may be acted on by a finger 114 extending forwardly and then sidewardly from the trigger 20. It will be evident from inspection of the drawings that when the trigger is pulled to fire the gun, the finger 114 bears against the part 112, and moves it downwardly to the broken line position 112', thus drawing the stop 108 to the broken line position 108', at which time it is withdrawn from the guide tube 28 preparatory to ejection of the projectile 24.

Another and simpler form of projectile stop means is illustrated in Fig. 13. In this case the projectile stop consists of a very light gauge spring 116, forward end of which is secured to guide tube 28 by means of spot welding or other suitable method. The rear end of the spring is bent downwardly and reversely with a relatively rounded surface 118. This is disposed in the path of the projectile 24, but the resistance to movement of the projectile is so slight that there is no appreciable change in the speed and trajectory of the projectile when it is fired. During the passage of the projectile, the spring moves upwardly slightly as is indicated by the broken line position 116' 118'. While the resistance to movement of the projectile is made very slight, it is never-

theless adequate to prevent gravitational escape of the projectile from the gun when pointed downwardly.

The mechanism so far described is equally applicable to a toy rifle, and this is illustrated in Fig. 14 in which the gun body is made of a single piece of relatively heavy gauge sheet metal bent downwardly until the lower edges are brought into edge to edge relation. The rear end of the gun body is secured to a wooden stock 120 by means of rivets 22. The mating edges of the gun body may be secured together, as for example by eyelets 124. An opening 126 is cut through the top of the gun body near the breech for passage of the projectiles 24, these being guided as before in a bent wire magazine 122. Trigger 20 and ejector finger 26 correspond to those previously described, and are similarly mounted in a frame 34, which in turn is secured to the gun body by tongue and slot connections 102. The guide tube 28 is fixed in place by tongues 92 at its rear end, all of these parts corresponding closely to the similarly numbered parts previously described. The guide tube 28 may be short, as shown in Fig. 14, or may be lengthened, but I find that the gun functions satisfactorily with even the short guide tube, particularly if the diameter of the external barrel 128 is very much larger than the diameter of the projectile. This is anyway preferably the case, in order to give the gun body realistic proportions, as well as to strengthen the same against bending or other damage during rough play.

The wire magazine 132 differs from magazine 22 at the lower end. This will be clear from Fig. 15, in which the wire sides 134 are bent outwardly at 136 and pass through mating holes in the side walls 138 of the gun body. The side edges of the opening 126 are recessed at 140 to hold the wire upright. As before, the wire magazine is readily removable by squeezing the sides 134 together as it is removed. This arrangement eliminates the ears 78 on the guide tube (Figs. 10 and 11) and is desirable when the gun body is too narrow at that point to accommodate the ears.

It is believed that the construction, method of assembly, and operation, as well as the advantages of our improved toy gun, will be apparent from the foregoing detailed description thereof. It will also be apparent that while we have shown and described our invention in several preferred forms, many changes and modifications may be made in the structures disclosed without departing from the spirit of the invention, as sought to be defined in the following claims.

We claim:

1. A toy simulating a trigger-operated portable gun such as a pistol or rifle, and comprising a gun body including a barrel for toy projectiles, a finger-operated pull trigger pivoted intermediate its ends in said gun body and movable from rest position to ejecting position in which a projectile is ejected from the gun, an ejector having its lower end pivoted on the trigger near the lower end of the trigger and also movable from rest position to ejecting position, means constraining the trigger and ejector to move together from ejecting position to rest position, the ejector being free to have a movement to

position separate from the movement of the trigger, the ejector being positioned and constructed for ejecting a projectile from said barrel each time the trigger is pulled through its range of movement, and a spring anchored to said gun body and connected to the ejector at a point intermediate the aforesaid pivots, said spring being normally tensioned to move the trigger about its pivot to rest position and thereby to move both the trigger and the ejector to rest position, movement of the trigger about the pivot during a trigger stroke acting to increase the said tension on the spring to thereby increasingly tension the ejector for a projectile ejecting operation, a holding means for the ejector and means operable during a trigger stroke for releasing the holding means.

2. The toy of claim 1 in which the holding means comprises a detent and in which the means for releasing the same comprises a link extending from said detent forwardly to a point in the path of movement of the upper end of the trigger.

3. A toy simulating a trigger-operated portable gun such as a pistol or rifle, and comprising a gun body including a barrel for toy projectiles, a finger-operated pull trigger pivoted in said gun body and movable from rest position to ejecting position in which a projectile is ejected from the gun, an ejector connected to the trigger and also movable from rest position to ejecting position, means constraining the trigger and ejector to move together from ejecting position to rest position, the ejector being free to have a movement to ejecting position separate from the movement of the trigger, the ejector being positioned and constructed for ejecting a projectile from said barrel each time the trigger is pulled through its range of movement, and a spring anchored to said gun body and connected to both the ejector and trigger, said spring being normally tensioned to move the trigger about its pivot to rest position and thereby to move both the trigger and the ejector to rest position, movement of the trigger about the pivot during a trigger stroke acting to increase the said tension on the spring to thereby increasingly tension the ejector for a projectile ejecting operation, a holding means for the ejector and means operable during a trigger stroke for releasing the holding means.

4. The toy of claim 3 in which the barrel has a breech portion open at the top for receiving toy projectiles.

5. The toy of claim 3 in which the holding means comprises a detent and in which the means for releasing the same comprises a link extending from said detent forwardly to a point in the path of movement of the upper end of the trigger.

6. The toy of claim 3 in which the barrel includes a guide tube, means for feeding toy projectiles into the guide tube, and in which the bottom of said tube is longitudinally slotted to receive the upper end of the ejector which strikes the rear end of a projectile in the guide tube when the ejector moves to ejecting position.

ANTHONY N. SMITH.
